UNITED STATES PATENT OFFICE.

FRANK F. FORSHEE, OF FLINT, MICHIGAN, ASSIGNOR TO WESTINGHOUSE ELECTRIC
PRODUCTS COMPANY, A CORPORATION OF MICHIGAN.

SCREW-SOCKET CONNECTION FOR RADIATORS.

1,425,638.

Specification of Letters Patent. Patented Aug. 15, 1922.

Application filed November 20, 1919. Serial No. 339,287.

To all whom it may concern:

Be it known that I, FRANK F. FORSHEE, a citizen of the United States, and a resident of Flint, in the county of Genesee and State 5 of Michigan, have invented a new and useful Improvement in Screw-Socket Connections for Radiators, of which the following is a specification.

My invention relates to electric heating 10 apparatus and particularly to radiant heaters, and it has for its object to provide a simple and inexpensive mounting for the heating element in apparatus of the character designated.

15 In a preferred embodiment of my invention, I provide the reflector of a radiant heater with a central axial opening and mount therein a rearwardly-extending, screw-threaded collar. I provide also a co- 20 operating screw-threaded clamping ring adapted to be screwed over the outer end of the collar and to clamp the heating element in axial alinement in proper position in the reflector.

25 Referring to the single sheet of drawings, Figure 1 is a side elevational view, partly in section, of a radiant heater embodying my invention, and Fig. 2 is a cross-sectional view, on an enlarged scale, of the particular 30 device embodying my invention.

Referring particularly to Fig. 1, a radiant heater 1 comprises a sheet-metal reflector 2 of concave form, a projecting wire guard 3 and a pair of curved supporting arms 4, 35 the lower ends of which are joined and securely mounted on a supporting base 5. A suitable handle 6 is provided for use in moving the radiant heater when desired.

The reflector 2 is provided with a centrally-located opening 7 and with a rearwardly-projecting tubular holder 8 that may be an integral part of the reflector body or be suitably fastened thereto. The outer part of the tubular holder 8 is provided 40 with screw threads 9, the diameter of the screw-threaded part having a larger diameter than the part in the opening 7. An annular clamping ring 10, having a screw-threaded part 11, is provided and 45 arranged to screw on the screw-threaded part of the holder 8. The ring 10 has an inwardly-projecting part 12 of somewhat smaller diameter than the screw-threaded part 11.

50 55 60 65 70 75 80 85 90 95 100 105 110

55 A heating element 13 comprises a tubular

heater 14 which is secured to a terminal block 15 by means of a bolt 16 and nuts 17. A spacing member 18 is provided near the outer end of the heater 13 to aid in securing the heater in the desired axial alinement 60 in the reflector 2. Standard contact terminals 19 are provided in the terminal block 15 to co-operate with a standard socket member when it is desired to operate the radiant heater. A metal shell 20 is suitably 65 secured to the outer end of the terminal block 15, the outer portion of the shell 20 having a reduced diameter and being adapted to co-operate with the portion 12 of the clamping ring 10, to maintain the heater 70 element 13 securely in position.

The heating element 13 may be removed by unscrewing the clamping ring 10 from the member 8, after which the complete heater unit may be withdrawn rearwardly.

75 I thus provide a simple and inexpensive device for securing a heater element in a radiant heater, which will permit of easily and quickly removing a damaged heater and of inserting a new one.

80 Various changes may be made without departing from the spirit and scope of my invention, and I desire that only such limitations shall be placed thereon as are imposed by the prior art or as are specifically set 85 forth in the appended claims.

I claim as my invention:

1. In an electric radiator, the combination with a reflector having an axial opening and a rearwardly removable unitary heating element in axial alinement in said reflector said heating element comprising a rearwardly-extending terminal block and a forwardly-extending heater, of rearwardly-extending means secured to said reflector in 90 said opening and having a portion provided with screw threads coaxial therewith for holding said heating element in axial alinement.

2. In an electric radiator, the combination with a reflector having an axial opening and a unitary heating element in axial alinement in said reflector comprising a rearwardly-extending terminal block and a forwardly-extending heater, of rearwardly-extending means secured to said reflector in 95 axial alinement with said opening and having a portion provided with screw threads coaxial with said opening for holding said heating element in axial alinement.

3. In an electric radiator, the combination with a reflector having an axial opening, a heating element extending forwardly of said reflector in axial alinement therewith, and 5 a rearwardly-extending terminal block permanently secured to said heating element, of a rearwardly-extending two-part screw-threaded tubular holder secured to said reflector in axial alinement with said opening 10 for holding said terminal block.
4. In an electric radiator, the combination with a reflector having an axial opening therein, a rearwardly-extending threaded collar in axial alinement with said opening, 15 and a forwardly-extending heating element having a double frusto-conical terminal block, of a threaded annular clamping member co-operating with said collar to hold said heating element in axial alinement in 20 said reflector.
5. In an electrical heating apparatus, the combination with a reflector having a central opening therein, a rearwardly-extending threaded collar secured to said reflector in 25 axial alinement with said opening, and a heater unit comprising a terminal block, a heater element axially alined with said block and a rod for maintaining said axial alinement of the tubular heater element with said 30 terminal block, of a clamping member co-operating with said collar for holding said heater unit in position.
6. In an electrical heating apparatus, the combination with a reflector having an axial 35 opening therein, a rearwardly-extending threaded tubular holder secured to said reflector in axial alinement with said opening, and a rearwardly-removable heater unit comprising a terminal block, and a heater element secured to said terminal block in 40 axial alinement therewith, of a threaded retaining collar mounted on said tubular holder for holding said terminal block.
7. In an electric radiator, in combination, 45 a reflector having an axial opening, a rearwardly removable unitary heating element axially alined in said reflector, said heating element comprising a terminal block and a heater extending forwardly of said terminal block, and means secured to said reflector in 50 said opening and having a portion provided with screw threads coaxial therewith for holding said heating element in axial alinement.
8. In an electric radiator, in combination, 55 a reflector having an axial opening, a unitary heating element in axial alinement in said reflector comprising a terminal block and a forwardly extending heater, and means secured to said reflector in axial alinement with said opening and having a portion provided with screw-threaded means coaxial with said opening for holding said heating element in axial alinement.

In testimony whereof, I have hereunto 65 subscribed my name this 6th day of November, 1919.

FRANK F. FORSHEE.
